UNITED STATES PATENT OFFICE.

ANTHONY STOKES, JR., OF CLEVELAND, OHIO.

HEATING APPARATUS FOR PROCESS-EMBOSSING.

1,325,217.

Specification of Letters Patent. Patented Dec. 16, 1919.

Application filed March 14, 1919. Serial No. 282,572.

To all whom it may concern:

Be it known that I, ANTHONY STOKES, Jr., a citizen of the United States, residing at Cleveland, in the county of Cuyahoga and State of Ohio, have invented a certain new and useful Improvement in Heating Apparatus for Process-Embossing, of which the following is a full, clear, and exact description, reference being had to the accompanying drawings.

The production of printing in raised characters applied to the face of the sheet is very popular as a substitute for embossing on account of its cheapness and the avoidance of the delay incident to having dies made. This character of printing is ordinarily called "process embossing" and consists of printing the matter, as a letter-head, for example, in suitable ink or sizing, and while the impression is wet subjecting it to a coating of glazing materials, which may be of resinous character, and then heating the sheet to fuse the material in place and give it a varnish effect.

The object of my invention is to provide a simple apparatus adapted to enable the application of the glazing material to the printed sheet, and the heating of the treated sheet to be effected very quickly and with certainty of satisfactory results. To this end I provide a movable receptacle, preferably a rotating drum, in which the sheets may be placed and in which granulated glazing material carried by the receptacle may be flowed over the printed impression, and I combine with this treating device a heater and a traveling conveyer so organized that the sheet may be readily taken from the receptacle and placed on the conveyer and carried by it through the heater at the proper speed to effect the desired fusing of the varnish granules.

My invention is illustrated in the drawings hereof and is hereinafter more fully explained, and its essential characteristics are summarized in the claims.

In the drawings, Figure 1 is a side elevation of an apparatus embodying my invention; Fig. 2 is a plan thereof; Fig. 3 is a vertical section through the heating chamber, as indicated by the line 3-3 on Fig. 1; Fig. 4 is a longitudinal vertical section

through the treating drum, on the line 4-4 on Fig. 2.

In Fig. 1 the frame of the machine is shown as comprising upright standards 10, a transverse brace member in the form of a platform indicated at 11 and boundary members 12 for a heating chamber connected with the upper ends of the standards. These members 12 are shown as comprising angle bars bent to form an open boundary frame, which is shown as of elliptical shape. These boundary frames are welded or otherwise secured to the standards 10. The standards also carry at their upper ends a pair of parallel longitudinal beams 15 which extend in each direction from the heater housing and support the conveyer belt or apron hereinafter described.

The heating chamber has ends 16 and a bottom 17 carried within the angle of the boundary members 12 and made of asbestos or other heat resisting material. The upper portion of the heating chamber is preferably hinged to allow ready access to the interior, for lighting the burners, cleaning the construction, etc. I effect this by mounting two cover members 18 on a hinge rod 19 carried by the end frame 12. The lower edges of these covers stand a suitable distance above the apron to be described to allow the sheets to readily travel into and out of the heater.

The heater in the chamber described is shown as comprising transverse burner tubes 20 (of which four are shown) above the apron and tubes 21 below it. Each of these tubes has a surrounding air inlet 22. These tubes are connected by elbows with a header 23, which may be supported by the adjacent frame 12. A suitable hose from the gas supply is connected to this header, and a key 25 adjusts the flame so that sheets may be properly heated but not scorched.

30 in Figs. 1 and 2 indicates an endless flexible conveyer belt or apron composed of slats linked together. This belt extends substantially horizontal through the heater housing and then extends over rollers 31 at the ends of the beams 15 and depends below the housing. Mounted on one of the standards 10 is a pulley 32 which is connected by a belt 33 with a pulley 34 on one of the apron rollers 31. By rotating this pulley

82 the apron is adapted to travel at the desired speed through the heater. For causing this travel I have shown a motor 35 mounted on the platform 11 and having on its armature shaft a pulley 36 connected by a belt 37 with a belt pulley 38 rigid with the pulley 32.

The treating drum is preferably carried by a frame secured to the horizontal beams 15 adjacent to the front of the machine. As 10 shown, I have mounted a pair of U-shaped straps 40 and 41 on these beams. These straps are parallel with each other and are inclined slightly backwardly from the vertical. At their highest points they have secured to them a longitudinal bar 43 which has downwardly bent arms 44 and 45. Journaled in these arms is a rotary shaft 46. Mounted on this shaft and guided by the straps 40 and 41 is a drum 50. This drum is 20 open at the front and has a thin wall, of sheet metal, for example, and a stiff back. The interior of the drum is coated with paint in which there is sand or carborundum grits. This gives a roughened surface. The back 25 is shown as provided with a reinforcing pad 52 which is secured to the shaft 46.

Suitable means are provided for rotating the drum 50. I have shown for this purpose a belt 55, which extends over the periphery 30 of the drum and about a pair of guide pulleys 56 and 57 carried by a bracket 58 secured to one of the beams 15 and thence onto a pulley 59 rigid with the pulleys 32 and 38.

In the operation of my device, varnish 35 granules (indicated at A in Fig. 4) are placed in the drum through its open front and lie on the lower portion of its peripheral wall. This drum being rotated, printed sheets fresh from the press are placed in 40 this drum face inward, and, due to the rotation, the material falls across the face of the sheet and adheres to the wet impression thereon. After the impression has thus received the varnish granules the sheet is 45 taken by hand out of the drum and placed on the belt immediately in front and below the drum and then travels through the heater, where the varnish material becomes fused and properly formed on the printing 50 base.

I find that it is desirable to drive the drum at about twice the speed of travel of the conveyer. The speed of the conveyer and the heat of the burners are mutually adjusted 55 so that there is no danger of scorching the sheet while the material will be fused in the minimum of time.

I find that this apparatus may conveniently be timed to take care of the out-put 60 of one job press, the operator taking the sheet as it comes to the press and placing it in the drum with one hand and with the other hand taking the treated sheet from the drum and placing it on the conveyer. Any 65 suitable receptacle (not shown) beyond the

other end of the conveyer may receive the sheets as they pass off of the end of the conveyer. The conveyer is long enough to allow sufficient time for the sheets to cool, so that the varnish material becomes set and the 70 sheets may pile up on each other without offsetting.

Having thus described my invention, what I claim is:

1. The combination, with a movable device adapted to carry a mass of granulated material and to receive sheets of paper placed in it by hand and carrying them into contact with the mass of granulated material, of a heater, and a traveling conveyer 75 extending beneath said device and through the heater for conveying the treated sheets from the treating device to the heater and delivering them.

2. The combination of a rotary receptacle 85 adapted to carry a mass of granulated material and to receive sheets of paper placed in it by hand and carry them into contact with the mass of granulated material, a traveling conveyer belt on which the sheet from the 90 receptacle may be laid, and a heater to which the conveyer may feed the sheet.

3. The combination of a rotary drum open at one side and provided with means for retaining granulated material therein, a conveyer belt traveling adjacent to the drum, and a heater through which the belt travels;

4. In a device of the character described, the combination of a drum open at one side and having its lower front edge elevated, 100 means for rotating the drum, a heater, and means for feeding sheets away from the drum and to the heater.

5. In a device of the character described, the combination of a drum open at one side 105 and mounted to rotate on an axis which is somewhat inclined in a direction to enable the drum to retain material in it, means for rotating the drum, and means for feeding sheets away from the drum.

6. The combination of a drum open at the front and mounted on an axis inclining slightly downwardly from the front, an endless belt passing beneath the drum and traveling rearwardly therefrom, and a heater 115 through which the belt travels.

7. The combination of a pair of frame beams, a conveyer carried between said beams, inclined frame members rising from the beams, a rotary drum carried by said frame members and tipped backwardly and open on its forward side, means for rotating the drum and for progressing the conveyer, and a heater to which the conveyer may feed a sheet.

8. The combination of a frame, a pair of horizontal beams carried thereby, rollers at the ends of the beams, an endless belt extending over the two rollers, a drum adjacent to the forward portion of the belt adapt- 130

ed to carry a mass of granulated material and to receive sheets of paper placed in it by hand and carry them into contact with the mass of granulated material, means for 5 rotating the drum and progressing the belt simultaneously, and a heater to which the belt may deliver a treated sheet.

9. The combination of a frame, a pair of horizontal beams carried thereby, rollers at 10 the ends of the beams, an endless conveyer belt extending over the two rollers, a drum above the forward portion of the belt mounted on an axis inclining slightly downwardly toward the rear, and means for rotating the 15 drum and progressing the belt simultaneously, and a heater carried by the frame at the rear of the drum, the belt traveling through said heater.

10. The combination of a frame, a pair of 20 horizontal beams carried thereby, rollers at the ends of the beams, an endless belt extending over the two rollers, a drum adjacent to the forward portion of the belt, and means for rotating the drum and progressing the 25 belt simultaneously, and a heater carried by the frame at the rear of the drum, the upper reach of the belt traveling through said heater and the lower reach passing below the heater.

11. The combination of a frame, a pair of 30 horizontal beams carried thereby, rollers at the ends of the beams, an endless belt extending over the two rollers, a rotary drum above the forward portion of the belt open on its 35 front side, and provided with means for retaining material therein and means for rotating the drum and progressing the belt simultaneously, and a heater carried by the frame at the rear of the drum, gas burners 40 therein above and below the belt.

12. The combination of a frame, a pair of horizontal beams carried thereby, rollers at the ends of the beams, an endless belt extending over the two rollers, a rotary drum 45 above the forward portion of the belt open on its front side, and provided with means for retaining material therein and means for rotating the drum and progressing the belt simultaneously, and a heater carried by the 50 frame at the rear of the drum, said heater comprising a transverse chamber, gas burners therein above and below the belt, and a

header with which said burners communicate and which is adapted to be connected with the gas main.

13. The combination with means adapted to carry a mass of granulated material and to receive sheets of paper placed in it by hand and carry them into contact with the mass of granulated material, of a frame, a 60 heater housing carried thereby comprising a transverse chamber having openings at the front and rear, horizontal beams carried by the frame, rollers mounted in the ends of said beams, an endless conveyer belt mounted on said rollers and having its upper reach 65 passing through the openings of the heater, and means for driving the belt.

14. The combination with means adapted to carry a mass of granulated material and 70 to receive sheets of paper placed in it by hand and carry them into contact with the mass of granulated material, of a frame, a heater housing carried thereby comprising a transverse chamber having openings at the 75 front and rear, horizontal beams carried by the frame, rollers mounted in the ends of said beams, an endless conveyer belt mounted on said rollers and having its upper reach passing through the openings of the heater 80 and its lower reach passing below the heater, means in the heater lying above and below the upper reach of the belt respectively, and means for driving the belt.

15. The combination of a frame, a heater 85 housing carried thereby comprising a transverse chamber having openings at the front and rear, horizontal beams carried by the frame, rollers mounted in the ends of said beams, an endless conveyer belt mounted on 90 said rollers and passing through the openings of the heater, burners in the heater lying above and below the upper reach of the belt respectively, a stationary upwardly extending frame carried by the belt support 95 at the front of the heater, a rotary drum carried by such rising frame on backwardly inclined axis and open at the front, and means for rotating the drum and driving the conveyer belt concurrently.

In testimony whereof, I hereunto affix my signature.

ANTHONY STOKES, JR.
